CRATE FOR USE IN RETORTS

Miren S. Canaday, Rochester, Minn., assignor
to Reid, Murdech & Co., Chicago, Ill., a cor-
poration of Illinois

Application May 29, 1930. Serial No. 456,853

8 Claims. (Cl. 220—84)

The invention relates to crates or baskets for retaining a load of cans in retorts.

In canning and preserving, it is now common practice to place a load of cans containing the goods in a crate which is suspended from an overhead carrier or hoist and adapted to be lowered into and lifted out of the retorts.

One object of the invention is to provide an improved crate for this purpose in which a side section is adapted to be moved into and out of closed position to facilitate removal of the cans from the crate.

Another object is to provide a crate with a pivoted section and means for securely locking it in its closed position, to retain the cans while the crate is in and being lowered into and removed from the retort. Another object of the invention is to provide an improved crate for this purpose which is simple in construction.

20 The invention consists in the several novel features hereinafter set forth and more particularly defined by claims at the conclusion hereof.

In the drawings: Fig. 1 is a side elevation of a crate embodying the invention. Fig. 2 is a plan. Fig. 3 is a plan of the locking device, the removable section being locked in closed position. Fig. 4 is a plan showing the lock released and the removable section partly swung out of its closed position. Fig. 5 is a perspective of the locking device and the joint between the fixed and pivoted sections of the crate. Fig. 6 is a sectional perspective on line 6—6 of Fig. 2.

The invention is exemplified in a crate composed of a fixed bottom, a semi-circular section 35 rigid with the bottom, and a semi-circular section which is pivoted so it can be swung laterally away from the bottom so that one side of the section will be open for conveniently dumping or unloading the cans. The bottom is formed of a ring 10 of flat metal and a series of parallel flat metal bars or slats 11 which are spaced apart and riveted to the top face of the ring 10.

The fixed semi-circular section is composed of a vertical series of semi-circular flat bars 14, 45 a pair of vertical bars 12, 12^a, which are secured to the outer faces of bars 14 adjacent their ends and cross-connected by an integral bar 12^b, and a series of intermediate vertical bars 13 which have their lower ends bent to underlie, and riveted to, ring 10. Bars 12, 12^a, and 13 are riveted or welded to the semi-circular bars 14 at their crossings to form a semi-circular side-section which is rigid with the bottom. The semi-circular bars 14 of the fixed section are aligned 50 with the semi-circular bars 16 of the pivoted

section. The removable side-section is composed of a series of semi-circular bars 16 which are vertically spaced apart and a series of vertical bars 15 which are riveted or welded to bars 16 at their points of crossing to form a rigid semi-circular section. The lower ends of bars 15 are bent to extend below ring 10. 60

One end of the movable section is pivoted to the fixed section by hinges 17, the members of which are respectively fixed to the vertical bar 65 15 adjacent one end of the movable section and the vertical bar 12^a of the fixed section.

The free end of the pivoted section is adapted to be securely locked to the contiguous end of the fixed section and to be released to permit the 70 contents to be dumped or for convenience in loading or unloading. This locking means comprises a vertical shaft 18 which extends through a sleeve formed of sections 19 which are welded to the inner faces of the semi-circular bars 14 of 75 the fixed section; a vertical rod 20 which is welded to the inner faces of the semi-circular bars 16 of the pivoted section; a set of hooks 21 which are rigid with and extend laterally from shaft 18 and have cam-recesses 22 which are 80 adapted to pass around the rod 20 and to draw it toward the fixed section, so that the contiguous ends of the semi-circular bars 14 and 16 will abut against each other and form, in effect, 85 continuous rings when the sections are locked together. The lower end of shaft 18 extends through and is rotatable in the ring 10. A handle or crank 23 is integrally formed with the rod 18 and extends laterally therefrom over the 90 fixed section. A ring 24, loose on the top semi-circular bar 14 of the fixed section, is adapted to be slipped over the outer end of the arm 23, as shown in Fig. 6, to interlock with a notch 24^a in said arm, to secure the arm so the pivoted section will be securely locked in its closed position. The bars 12, 12^a and 12^b of the fixed 95 section form a hanger for the crate. The upper ends of vertical bars 12, 12^a are formed with holes 25, in which the ends of a lifting bail 26 are pivoted.

The crate is adapted to be handled by an overhead carrier or hoist and applied to the bail. In practice, the crate is loaded with cans from a machine or by hand while the pivoted section is closed. If it should be desired to load the crate from the side, the cans can be stacked on the bottom while the pivoted section is open. While the side-section is closed and locked, and when a load of cans has been placed therein, the crate with the load is lowered into the retort. After 100 the contents of the crate have been processed 105 110

in the retort, the carrier or hoist will be applied to bail 26, and the loaded crate will be lifted out of the retort and transported to the point where it is desired to dump the load of cans. The operator will slip ring 24 off the locking arm 23 and swing the latter inwardly to rock shaft 18, so the hooks thereon will be disengaged from the vertical rod 20 on the pivoted section. The latter can then be swung into its open position. The cans 10 will then fall out of the crate, or, if desired, the bottom may be tilted sufficiently to dump the load through the open side of the crate at any desired point.

The invention exemplifies a crate for use in 15 retorts which comprises a movable side to facilitate the dumping of the load from the crate; which is simple in construction, and can be produced at a low cost; and which is provided with reliable locking means for securing the pivoted section in 20 closed position to prevent accidental discharge of the load from the crate while it is being handled or transported.

The invention is not to be understood as 25 restricted to the details set forth, since these may be modified within the scope of the appended 30 claims, without departing from the spirit and scope of the invention.

Having thus described the invention, what I 35 claim as new and desire to secure by Letters Patent, 30 ent, is:

1. A crate comprising a bottom and a fixed 35 side section formed of bars of metal secured together, a section pivoted to the fixed section so as to swing laterally and formed of metal bars secured together the bottom being rigid with the 40 fixed side and projecting therefrom to form a complete rigid bottom for the entire crate, and means for locking the pivoted section in its closed position.

2. A crate comprising a bottom and a fixed 45 side section formed of vertical and circumferential bars of metal secured together, a section pivoted to the fixed section so as to swing laterally and formed of metal bars secured together the bottom being rigid with the fixed side and projecting therefrom to form a complete rigid bottom for the entire crate, means for locking the 50 pivoted section in its closed position, and a lifting bail pivoted to two of the vertical bars of the fixed section adjacent the contiguous ends of the pivoted section.

3. A crate comprising a bottom formed of a 55 ring and slats secured thereto, a fixed side-section formed of vertical and substantially semi-circular bars of metal secured together the bottom being rigid with the fixed side and projecting therefrom to form a complete rigid bottom for the entire crate, said vertical bars being secured to said ring, and a section pivoted to the fixed section so as to swing laterally and formed of semi-circular and vertical metal bars secured together,

means for locking the pivoted section in closed position, and a lifting bail connected to the fixed section adjacent the contiguous ends of the pivoted section.

4. In a crate of the character described, the 80 combination of a bottom and a pair of side sections one of which sections is rigid with the bottom and the other of which is pivoted to the fixed section, said bottom and sections being composed of metal bars rigidly secured together, and 85 a locking device comprising a vertical rock-shaft pivoted to one side-section and provided with a plurality of hooks for securing the free end of the pivoted section.

5. In a crate of the character described, the 90 combination of a bottom and a pair of side-sections one of which sections is rigid with the bottom and the other of which is pivoted to the fixed section, said bottom and sections being composed of metal bars rigidly secured together, 95 and a locking device comprising a rod fixed to one of the sections, a vertical rock-shaft pivoted to the other section and provided with a plurality of hooks for engaging the load, and means for securing the shaft in locked position.

6. In a crate of the character described, the 100 combination of a bottom and a pair of side sections one of which sections is rigid with the bottom and the other of which is pivoted to the fixed section, said bottom and sections being composed of metal bars rigidly secured together, 105 and a locking device comprising a rod fixed to one of the pivoted sections, a rock-shaft pivoted to the fixed sections and provided with a plurality of hooks for engaging the rod, and means for securing the shaft.

7. In a crate of the character described, the 110 combination of a bottom and a pair of side sections one of which sections is rigid with the bottom and the other of which is pivoted to the fixed section, said bottom and sections being composed of metal bars rigidly secured together, 115 and a locking device comprising a vertical rock-shaft, sleeve-sections in which the shaft is pivoted, secured to the one section, and a plurality of hooks on the shaft for engaging the other section.

8. In a crate of the character described, the 120 combination of a bottom and a pair of side sections one of which sections is rigid with the bottom, and the other of which is pivoted to the fixed section, said bottom and sections being composed of metal bars rigidly secured together, and a locking device comprising a vertical rod fixed to the pivoted section, sleeve-sections fixed to the 125 fixed section, a vertical shaft in said sleeve-sections, provided with cam-hooks for engaging said rod, an arm on the upper end of the shaft, and means for securing the shaft when the pivoted section is locked.

MIRON S. CANADAY.
